CONTAINER FOR FOOD PRODUCTS

Mayo D. Krause, Burlingame, Calif.

Application February 12, 1948, Serial No. 144,429

Term of patent 3½ years

(Cl. D58—12.6)

To all whom it may concern:

Be it known that I, Mayo D. Krause, a citizen of the United States of America, residing at Burlingame, in the county of San Mateo, and State of California, have invented a new, original, and ornamental Design for a Container for Food Products, of which the following is a specification, reference being had to the accompanying drawing, forming a part thereof.

In the drawing:

Fig. 1 is a side elevational view and

Fig. 2 is a perspective view of a container for food products, showing my new design.

The undisclosed side of the present design is of similar appearance to the side shown.

I claim:

The ornamental design for a container for food products, substantially as shown and described.

MAYO D. KRAUSE.
